INTERNAL-COMBUSTION ENGINE.

Application filed November 27, 1918. Serial No. 264,312.

The present invention relates to internal combustion engines and more particularly to devices for increasing the normal charges of explosive mixture taken into the cylinders of such engines. Internal combustion engines, as at present generally constructed, draw into their cylinders on each intake stroke a charge of explosive mixture, the volume of which is limited by the volume of the space swept by the piston. When the surrounding atmospheric pressure is reduced and the air becomes rarefied, as by the changes in altitude, the charge, although of the same volume, is correspondingly rarefied and the amount of oxygen available for combustion is proportionately reduced and the power lessened.

With stationary engines and even with automobile engines such loss of power due to altitude is not a particularly serious matter, because the altitudes at which such engines are commonly operated are comparatively low so that the loss is small, and further because by a slight increase in size and weight, which is not usually objectionable, the maximum power required at the higher altitudes may still be secured.

In the case of aeroplane engines, however, this loss of power due to altitude is very objectionable, since not only are these engines operated at very high altitudes where the atmospheric pressure is greatly reduced, but the permissible weight of the engines is so limited that it is generally impractical to increase their size to any substantial extent.

These excessive changes in atmospheric pressure to which the aeroplane engine is subjected not only reduce the quantity of the charge but produce variations in its quality which tend further to reduce its power from the maximum.

Another condition peculiar to the operation of aeroplane engines, which may interfere with their developing maximum power, is the great range of atmospheric temperature to which they may be subjected within a comparatively brief period of time, a difference of more than 100° Fahrenheit between the temperature on the ground and that prevailing at fifteen thousand to twenty thousand feet altitude not being unusual.

It is necessary, therefore, to provide aeroplane engines with devices for furnishing

the carburetor or intake manifold or both with the proper amount of heat to insure perfect vaporization of the fuel under varying temperature conditions.

One of the objects of the present invention is to provide an internal combustion engine with devices for compensating for the reduction and variation in the charge due to the rarefaction of the atmosphere at high altitudes.

A further object of the present invention is to provide compensating devices of the above type which are either automatically or hand controlled, at the will of the operator.

Still another object of the present invention is to provide means which shall maintain the carburetor or intake manifold at the proper temperature for perfect vaporization of the fuel, irrespective of temperature changes due to variations in altitude.

A still further object is to devise compensating mechanism of the above kind which shall be adapted for attachment to, and use upon, many of the present types of aeroplane engines.

With these and other objects in view as will be apparent to those skilled in this art from the following specification, the present invention consists in the devices and combinations of devices hereinafter described and claimed.

In the accompanying drawings which illustrate what is now considered the preferred embodiment of the invention, Figure 1 is a view in side elevation, with certain parts broken away, of a portion of an aeroplane motor embodying the present invention; Fig. 2 is an end elevation, with the motor shaft in section on the line 2-2 of Fig. 1, looking toward the right, showing the fan for compressing the rarefied air and the controlling mechanism therefor; Fig. 3 is a vertical sectional view on an enlarged scale of the controlling mechanism, taken on the line 3-3 of Fig. 1, looking toward the right, and Fig. 4 is a vertical sectional view of the regulator valve for controlling the heating or cooling of the intake manifold according to the altitude.

In Fig. 1 of the drawings, the rear portion of the motor is indicated generally at 5, one of the cylinders at 6, the crank shaft at 11a

7, the intake manifold at 8, and carbureter at 9. An oil pump 10, driven from the crank shaft through gearing 11, draws oil from a supply tank 12 and forces it, under pressure, through a conduit 13 and branch conduits to the bearings and gearing in various parts of the motor, the oil returning to the sump 14 from which it is drained, back into the supply tank.

10 The motor is mounted on the longitudinal members 15, 15 of the fuselage which also support a frame 16 of inverted V-shape carrying the fan casing 17 and the regulating mechanism 18. The fan casing 17 which is 15 of the usual involute type, comprises two sections bolted together and provided with a radial intake passage 19 and a tangential discharge passage 20. The intake passage 19 is divided at the fan end into two passages 20 on opposite sides of the fan, through which air is permitted to enter the fan casing axially. The outlet or discharge passage 20 is connected by means of a short length of hose 21, with the air-intake 22 of 25 the carbureter 9.

Within the fan casing is a centrifugal fan 23 comprising a plurality of substantially radial blades 24, integrally formed with the central web 25 and the fan shaft 26 which 30 is mounted to rotate in suitable ball bearings 27 and 28, being driven at high speed from a countershaft 29 through intermeshing double herringbone gear wheels 30 and 31. The countershaft 29 is adapted to be driven 35 from the crank shaft 7 of the motor through a belt 32 which passes over a pulley 33 on the crank shaft and a pulley 34 on the counter-shaft. The ratio between the pulleys 33 and 34 being 2 to 1 and the ratio between the 40 gear wheels 31 and 30 being 5 to 1 it will be seen that the fan will be driven at an extremely high rate of speed. The peculiar design of the fan blades, together with the integral formation of the blades, the connecting webs and the fan shaft serve to increase the strength and efficiency of operation 45 of the fan and render it particularly adapted to rotate at high speed.

The entrance of foreign matter into the 50 fan casing is prevented by a screen 35 of wire mesh, which covers the intake opening 19, while a muffler 36 is attached thereto to reduce the noise produced by the inrush of air.

While the motor is running in low altitudes, where the atmospheric pressure is not sufficiently reduced to cause an appreciable loss of power, the belt 32 is permitted to pass loosely over the pulleys 33 and 34 and the fan 55 is not driven. When, however, the aeroplane reaches such an altitude that the atmospheric pressure falls below the predetermined degree, a belt-tightener pulley 37, which is part of the controlling or regulator mechanism, is moved into engagement with the belt 32, 60 tightening it more and more as the altitude 65

increases so that the fan will be driven at the proper speed to maintain the pressure in the air-intake of the carbureter and in the gasoline tank at substantially the same approximate sea-level pressure, irrespective of the 70 altitude actually attained.

The mechanism for moving the belt-tightener to vary the speed of the fan and thus the pressure developed is as follows: The belt-tightener pulley 37 is mounted by 75 means of suitable ball bearings to turn on an axle 38 fixed between ears 39 projecting from a head 40 carried at one end of a hollow plunger 41. The opposite end of the plunger is closed by a plug 42 to which a leather 80 washer 43 is secured by a bolt 44. The plunger is adapted for longitudinal movement in a belt-tightener cylinder 45, the pressure of the oil in the lubricating system of the motor being utilized to move the 85 plunger toward the belt 32 while the springs 46 are provided for moving it in the opposite direction. The oil is conducted from the motor casing through a conduit 47 and passage 48 in the wall of the belt-tightener 90 cylinder to a chamber 49 behind the plunger. Thence the oil flows through a passage 50 to a valve casing 51, from which it is conveyed by the return pipe 52 to the sump of the motor. 95

When the pressure of the oil in the chamber 49 at the head of the belt-tightener cylinder 45 rises, the plunger 41 is forced outwardly to cause the pulley 37 to tighten the belt and thus drive the fan. The greater the oil pressure, the greater the movement of the plunger, the tighter the belt and the higher the speed of the fan. When the pressure of the oil in the cylinder 45 diminishes, the springs cause a return movement of the 100 belt-tightener, a loosening of the belt, and a reduction in fan speed. 105

The pressure of the oil behind the plunger 41 is controlled by a valve 53 in the valve casing 51, the valve being operated to effect an increase of the pressure by the expansion of a sylphon bellows 54 under the influence of a helical spring 55 and to effect a reduction of pressure by the contraction of the bellows due to the existence of a partial vacuum 110 therein; the bellows expanding or contracting according as the pressure within the sylphon cylinder 56, which encloses the bellows, is diminished or increased. With the valve 53 in wide open position, as shown in Fig. 3, which corresponds to normal, sea-level pressure, the oil is permitted to pass freely through the chamber 49, having no effect upon the plunger. A movement, however, of the valve toward the left as the aeroplane rises retards the escape of the oil, and the increased pressure behind the plunger moves it toward the opposite end of the cylinder, bringing the belt-tightener pulley into 115 engagement with the belt. The belt-tight- 120

ener and sylphon cylinders are cast integrally and provided with a bracket 57 which is bolted to the frame 16 and has formed therein a longitudinal guideway 58 into which projects a lug 59 on the plunger head 40 to maintain the axis of the belt-tightener pulley 37 always parallel to the axes of the fan and motor shafts.

The sylphon bellows comprises an expandible tube 60, the ends of which are closed by disks 61 and 62 which are provided with inwardly projecting hubs 63 and 64 respectively. Each having a threaded socket at both its inner and outer extremities. Within the bellows is a rod 65 which is screwed into the inner socket of the hub 64 and telescopes into a sleeve 66 which is in turn screwed into the inner socket of the hub 63. A pin 67 secured in the rod 65 near its free end projects through oppositely disposed elongated slots in the sleeve 66, thus preventing twisting of the rod or the sleeve relatively to each other and protecting the bellows from torsional strain. The helical expansion spring 55 is interposed between the disks 61 and 62, surrounding the sleeve 66 and the hubs 63 and 64, and is prevented from coming into contact with the expandible tube 60 by annular retaining ribs 68 and 69 on the disks 61 and 62 respectively. The bellows are sealed after the air has been exhausted sufficiently to produce approximately an 18" vacuum which keeps the bellows contracted at normal atmospheric pressure against the expansive action of the spring 55. Into the outer threaded socket in the hub of the disk 61 is screwed the valve 53 which is mounted for longitudinal movement in the valve casing 51 at one end of the sylphon cylinder and has a reduced portion 70 normally permitting a free flow of oil through the passage 50. A rod 71 is screwed into the outer socket in the hub of the disk 62 and is mounted in a bearing 72 in the opposite end of the sylphon cylinder. The rod 71 is held against longitudinal movement by means of a spring pressed detent or ball 73 which rests in an annular groove 74 in the rod. The valve 53 and the rod 71 support the sylphon bellows centrally in the sylphon cylinder. The head of a screw 76 in the outer end of the valve member, by engagement with an annular shoulder 77 on the valve casing, limits the contraction of the bellows and locates the valve in its wide open position.

The interior of the sylphon cylinder is in communication with the discharge passage 20 of the fan by means of a pipe 75. When the fan is not in operation the pressure transmitted from the fan discharge pipe 20 through pipe 75 to the sylphon cylinder is the pressure of the atmosphere. The atmospheric pressure on the ground is sufficiently in excess of the partial vacuum in the

bellows to counteract the expansive force of the spring and maintain the bellows in its normal contracted condition with the valve wide open, as shown in Fig. 3. When, however, the aeroplane rises and the atmospheric pressure falls, the reduced pressure is communicated through the pipe 75 to the interior of the sylphon cylinder and the helical spring is permitted to expand, thus moving the valve 53 to the left of Fig. 3, and checking somewhat the flow of the oil. As the flow is retarded, the oil accumulates behind the plunger, the pressure builds up and the plunger is forced outwardly until the belt-tightener pulley engages the belt and tightens it sufficiently to start the fan.

By making the sylphon bellows so sensitive that a reduction in pressure of a few ounces will produce the extreme limit of movement of the bellows and valve, it is possible by connecting the sylphon cylinder 54 with the discharge pipe 20 of the fan, to maintain a substantially constant pressure in the air intake 22 in the carburetor, irrespective of the engine speed; whereas, if the sylphon cylinder was in communication with the atmosphere and the sensitiveness of the sylphon bellows was correspondingly adjusted, variations in engine speed would produce corresponding variations in fan speed and, therefore, in the pressure in the air intake of the carburetor.

The gasoline tank 79, from which the gasoline is fed to the carburetor through a pipe 80, is in communication, above the level of the gasoline, with the discharge passage of the fan casing (see Fig. 1), so that the gasoline is subject to atmospheric pressure when the fan is inactive and to the pressure produced by the fan when it is active. Thus, not only are the same relative pressure of gasoline in the tank and air in the carburetor intake maintained irrespective of the altitude (within the range or limits of the apparatus), but substantially the same absolute pressures as well. Both the quantity and quality of the charge therefore remain constant and the motor is enabled to develop its full power at high altitudes as effectively as at sea-level.

In order to permit the operator to control manually the intake pressure, as for example, in the case of derangement of the sylphon cylinder, a T-shaped lever 81 has been provided, having a pin and slot connection at 82 with the outer end of the rod 71 and fulcrumed at 83 between lateral ears 84 on a split collar 85 clamped on a sleeve 86 projecting from the sylphon cylinder. Movement of the lever 81 will dislodge the spring pressed detent 73 from engagement with the groove 74 and, through the pin and slot connection between rod 65 and sleeve 66, actuate the valve 53. Suitable control wires may be secured in apertures at opposite ends of the

lateral extension 87 of the lever and brought to the proper locality to permit control of the valve by the aviator.

The gearing and bearings in the fan casting may be conveniently lubricated from the main oil pressure system of the motor. As shown in Fig. 1, the oil is forced by the pump 10 through a reducing valve 90, a conduit 91, and branch conduits 92 and 93, to the fan casing and is returned through tubing 94 to the sump of the motor.

The high speed at which the fan is operated and the compression of the air which is thereby effected results in a very substantial rise of temperature of the air. At the higher speeds of operation of the fan the temperature rise of the air is so great as to interfere seriously with the maximum power development by the engine. At the lower altitudes where the fan is not in operation or is rotating at a comparatively low rate of speed heat must be supplied from some external source to the carburetor or to the intake manifold for the proper vaporization of the fuel. At moderate altitudes and at moderate fan speed the heat of the air delivered by the fan is sufficient and additional heat is not required. At the higher altitudes and higher fan speeds heat in excess of the desired amount is supplied by the air from the fan, and this excess must be withdrawn if the engine is to develop its maximum power.

Accordingly, I have provided the intake manifold with a water jacket connected with two sources of circulating water. One source is the water cooling system of the engine whereby heat may be supplied to the manifold at the lower altitudes. The other source is an independent cooling system whereby heat may be absorbed from the intake manifold at the higher altitudes. Automatic devices are provided for controlling the connection of these two sources to the water jacket of the manifold so that at lower altitudes heat is supplied to the intake jacket from the cooling system of the engine. At moderate altitudes both supplies are cut off and no heat is supplied or withdrawn from the manifold. At the higher altitudes the cooling system is connected with the manifold jacket to withdraw the surplus heat caused by the operation of the fan.

In Fig. 1 the circulating pump 101 of the engine is connected through the pipe 102 to the water manifold 103. The hot water from the top of the cylinders is returned through the pipe 104 to the thermostatic device 105 and thence either directly to the pump when the engine is cold or through a cooling radiator (not shown) connected to the thermostatic device 105 through the pipe 106 and with the pump 101 by the pipe 107.

At the lower altitudes water from the water manifold 103 is led through the pipe

110 to the automatic water valve 111 and thence through the short pipe 112 into the bottom of the jacket 113 of the intake manifold which, at its top, is connected with the water jacket at the head of the cylinder by the pipe 114 provided with the check valve 115.

The cooling circulatory system for withdrawing the excess heat from the intake manifold comprises the pipe 116 leading from the water valve 111 to a circulating pump 117 driven by the propeller blades 118 which are rotated by the blast from the aeroplane propeller. This water pump forces water through the pipe 119 to the cooling radiator 120 whence it is led to the top of the intake through the connection 121. Thus the movement of the water in the jacket of the intake is in the opposite direction for cooling from what it is for warming, being forced downwardly through the jacket and through the pipe 112 to the water valve 111 when absorbing heat at the higher altitudes, and flowing in the opposite direction through the pipe 112 and water jacket 113 when supplying heat at the lower altitudes.

The construction of the water valve 111 is illustrated in Fig. 4. The valve comprises a substantially cylindrical casing tapped at one side at 125 and 126 to receive the pipes 110 and 112 respectively, and on the other side at a somewhat higher point at 127 to receive the pipe 116. A piston valve 128 is arranged to control communication between these various pipes. With the valve as shown in Fig. 4, pipes 110 and 112 are in communication, thus permitting water from the engine cooling system to pass through the intake jacket to warm the intake. If the piston valve 128 were depressed against the tension of spring 129 to the position shown in dotted outline, the opening 125 to pipe 110 would be closed and pipes 112 and 116 would be in communication when water from the cooling radiator 120 would be forced downwardly through the intake jacket to cool the same.

The piston valve 128 is actuated by means of a piston 130 connected to the valve by a stem 131, the piston being actuated by the oil pressure in the oil pipe 47 which is connected by a pipe 132 threaded into the opening 133 in the head or cap 134 of the valve casing 111. By means of the adjusting screw 135 the compression of spring 129 can be so adjusted that at the lower altitudes pipes 110 and 112 will be in communication; at the higher altitudes pipes 112 and 116 will be in communication. At intermediate altitudes the openings or ports will be more or less covered by the valve and the circulation of the heating or the cooling water, as the case may be, will be correspondingly reduced or even cut off altogether.

Thus the amount of heat available for

vaporization of the fuel will be varied according to the requirements and conditions to insure perfect vaporization and maximum power development.

5 The operation of my improved aeroplane engine is as follows:—

When the engine is first started under normal sea level pressure, the sylphon bellows controlling the oil valve 53 is contracted as shown in Fig. 3, so that the oil flows freely through the controlling mechanism without developing sufficient pressure to move the belt-tightener or the automatic water valve. The fan, therefore, remains stationary and the inlet manifold jacket is supplied with hot water from the engine cooling system. As the aeroplane rises the atmospheric pressure begins to diminish and at the desired altitude, say five thousand feet, 10 a sufficient reduction in pressure has occurred to cause the sylphon bellows to expand slightly and partially to close the oil valve 53. As a result the flow of oil is retarded and its pressure is raised sufficiently 15 to cause the belt-tightener pulley to put a slight tension upon the belt to start the fan in operation at relatively low speed. As the aeroplane rises higher and the atmospheric pressure further diminishes, the belt-tightener pulley effects a further tightening of the belt with a consequent higher fan speed, which results in an increased compression of the air in the air intake to compensate for the reduction of atmospheric pressure. In 20 the meantime the automatic water valve has begun to move under the increased oil pressure, and as the oil pressure continues to rise the circulation of hot water from the engine through the intake manifold jacket is correspondingly reduced until it is finally 25 cut off altogether, the heat in the air in the carburetor intake generated by the now rapidly revolving fan being sufficient to insure vaporization of the fuel. With still higher altitudes, the belt will be further tightened to give still higher fan speeds and cooling water will be admitted to the water jacket by the action of the automatic water valve. When the aeroplane reaches an altitude corresponding to the range or limit of the apparatus, there will be no appreciable slipping of the belt and the fan will be driven at maximum speed, the automatic water valve being then in position to give the 30 freest circulation of cooling water through the intake manifold jacket.

If, when the aeroplane is at intermediate altitudes, the speed of the engine be reduced, the reduction in air pressure in the carburetor intake due to the decreased speed of the fan will at once be transmitted to the sylphon cylinder where it will cause an immediate expansion of the bellow, with a resulting tightening of the belt and restoration of 35 the speed of the fan. A return of the en-

gine speed to normal maximum speed operates in the reverse manner to loosen the belt sufficiently to prevent any substantial increase in fan speed. Thus, not only is the pressure in the carburetor intake maintained 40 at substantially normal sea level pressure irrespective of the actual altitudes of the aeroplane and the surrounding atmospheric pressure, but this condition of substantially normal sea level pressure in the carburetor intake is maintained irrespective of variations 45 in engine speed, within the range of the apparatus.

It will be observed that the fan with its driving and controlling mechanism is compactly arranged all upon the same frame. Thus the apparatus may be readily attached to many different types of aeroplane engine, it being necessary to provide only a belt drive from some convenient engine shaft, 50 a hose connection to the carburetor intake, and simple oil pipe connections with the oiling system of the engine.

While I have shown and described the present invention as embodied in an aeroplane engine, it is to be understood that my invention is not limited thereto, but that its several features may be employed to advantage either alone or with one another in other types of engines. Nor is the present invention limited to the specific constructions shown and described, but the form and arrangement of the parts may be varied within the limits defined by the claims.

Having shown and described what is now 100 considered to be the preferred form of the invention and explained its mode of operation, what is claimed is:

1. The combination with an internal combustion engine having a shaft, of means for delivering gaseous mixture to the engine, and auxiliary devices, including a normally inoperative compressor and variable speed, driving connections between the compressor and shaft, for delivering the gaseous mixture under a supplementary pressure when the atmospheric pressure is reduced.

2. The combination with an internal combustion engine having a shaft, of means for delivering gaseous mixture to the engine, auxiliary devices including a compressor which is inoperative at normal atmospheric pressure and which operates automatically when the atmospheric pressure is reduced below normal, to deliver the gaseous mixture to the engine under a supplementary pressure, and variable speed driving connections between the compressor and shaft.

3. The combination with an internal combustion engine having a shaft, of means for delivering gaseous mixture to the engine, and devices including a compressor and driving connections between the compressor and shaft operating automatically at varying speeds relatively to the engine to main- 130

tain the pressure of the gaseous mixture substantially constant irrespective of changes in atmospheric pressure.

4. The combination with an internal combustion engine having a shaft, of means for delivering gaseous mixture to the engine, and devices including a compressor and driving connections between the compressor and shaft operating automatically at varying speeds relatively to the engine to maintain the pressure of the gaseous mixture substantially constant irrespective of changes in engine speed.

5. The combination with an internal combustion engine having a shaft, of means for delivering gaseous mixture to the engine including a rotary blower and devices driven from the shaft for operating the blower at different speeds relatively to the engine speeds for different atmospheric pressures.

6. The combination with an internal combustion engine having a shaft, of a carbureter having an air-intake, a rotary blower adapted to force air into the air-intake of the carbureter, variable speed connections between the blower and shaft for operating the blower from the engine, and means for controlling the speed of the blower.

7. The combination with an internal combustion engine, of means for delivering gaseous mixture to the engine, said means including a centrifugal fan and casing, a belt for driving the fan from the engine, a belt-tightener pulley, and devices for adjusting the position of said pulley to control the speed of the fan.

8. The combination with an internal combustion engine, of a carbureter, means for delivering gaseous mixture to the engine, including a centrifugal fan and casing, frictional devices for driving the fan from the engine, and means for controlling said devices comprising a cylinder and a plunger, means for supplying oil continuously to the cylinder behind the plunger under pressure, a conduit for the escape of the oil, and a valve in said conduit for regulating the escape of the oil.

9. The combination with an internal combustion engine, of a carbureter having an air-intake, a fan, a fan casing connected with the air-intake of the carbureter, means including a belt for driving the fan from the engine, a belt-tightener pulley, means for adjusting the position of said pulley to regulate the speed of the fan, said means comprising a cylinder, a plunger movable therein, and an oil pump, connections between the pump and the cylinder for conveying oil to the cylinder, a return conduit for the escape of the oil, an escape valve, and means responsive to variations in air pressure for operating said valve to control the escape of the oil.

65 10. The combination with an internal

combustion engine having a shaft, of means for supplying gaseous mixture to the engine, means including a normally inoperative compressor and driving connections between the compressor and shaft for creating supplementary pressure on the gaseous mixture, and devices for controlling said means, said devices including a valve, a member having an air-tight expansion chamber connected with said valve, and connections for subjecting said member to the air pressure.

11. The combination with an internal combustion engine having a cooling circulatory system, a carbureter, and an intake manifold, of a water jacket for the manifold, connections between the water jacket and the circulatory system of the engine for warming the manifold, an auxiliary cooling system, connections between said system and the jacket for cooling the intake manifold, and devices for controlling the connections between the jacket and the circulatory systems.

12. The combination with an internal combustion engine having a carbureter, means for supplying the carbureter with air compressed above the surrounding atmospheric pressure, devices controlling the amount of heat available for vaporization of the fuel, and means controlling said devices in accordance with the degree of pressure of the air supplied to the carbureter.

13. The combination with an internal combustion engine having a carbureter and connections between the carbureter and the engine, a fan for supplying air to the intake of the carbureter at a substantially uniform pressure irrespective of the surrounding atmospheric pressure, devices for absorbing from the air heat created by the fan, and automatic means for varying the action of said devices to increase the heat absorption thereof as the speed of the fan is increased.

14. The combination with an internal combustion engine having a carbureter and connections with the engine, means including a water jacket for supplying and absorbing heat adjacent the carbureter, a supply of hot water and a supply of cold water, connections between said supplies and said jacket, and automatic means controlling said connections to permit water to flow from one or from the other or from neither of said supplies according to the requirements.

15. The combination with an internal combustion engine having a carbureter and connections with the engine, of devices for controlling the amount of heat available adjacent the carbureter for vaporization of the fuel, and means actuated primarily by changes in atmospheric pressure for automatically controlling said devices.

16. The combination with an internal combustion engine having a cooling circulatory system and a carbureter and an intake

manifold connecting the same with the engine, of a water jacket for the manifold, connections between the circulatory system of the engine and the water jacket, an independent circulatory system, connections between the water jacket and both of said circulatory systems, said connections including a three-way valve and a pipe between said valve and the jacket common to both sets of connections, and connections for actuating the three-way valve to connect the jacket with either of said systems or to disconnect it from both.

17. Mechanism for supplying air to the air intake of the carburetor of an internal combustion engine having a shaft, comprising a frame, a fan casing carried by the frame having an outlet port adapted to be connected to the carburetor air intake, a rotary fan within the casing, variable speed devices carried by the frame for driving the fan from the engine shaft, and controlling mechanism carried by the frame responsive to variations in air pressure for controlling the variable speed devices.

18. Mechanism for supplying air to the air intake of the carburetor of an internal combustion engine, comprising a supporting frame, a fan casing carried by the frame and having a discharge port adapted to be connected to the carburetor intake, a rotary fan within the casing, a shaft, a belt pulley, transmission gearing between said shaft and the rotary fan, a pressure cylinder, a piston, a belt-tightener pulley actuated by the piston, a control cylinder in communication with the discharge port of the fan casing, a control valve, pressure control devices in the control cylinder for actuating the valve, and connections for conveying fluid to the pressure cylinder and through the valve.

19. The combination of an internal combustion engine having a shaft, of a carburetor having an air intake, a compressor driven from the engine shaft at varying speed relatively to the shaft for delivering air directly to the intake, and means for controlling the speed of the compressor to maintain substantially constant pressure in the intake irrespective of variations in atmospheric pressure.

20. The combination with an internal combustion engine having a carburetor and connections, of devices for supplying and for abstracting heat from the connections adjacent the carburetor, and means responsive to variations in atmospheric pressure for controlling said devices.

21. The combination with an internal combustion engine having a shaft, of a carburetor, an air intake, a rotary blower driven from the engine shaft for delivering air to the intake, means for varying the speed of the blower to maintain substantially constant pressure in the air intake ir-

respective of variations in atmospheric pressure, a fuel tank and a connection from the air intake to the top of the fuel tank.

22. Means for supplying an explosive mixture of hydrocarbon and air to explosion engines having shafts comprising a mixing device having means for supplying hydrocarbon and air thereto, the air supplying means embracing a pressure device driven from the engine shaft at varying speed relative to the shaft for supplying constant air pressures to the mixing device, and means responsive to altitudinal variations of atmospheric conditions for regulating the pressure device.

23. Means for supplying an explosive mixture of hydrocarbon and air to explosion engines having shafts comprising a mixing device having means for supplying hydrocarbon and air thereto, the air supplying means embracing a pump and variable speed driving connections between the pump and engine shaft, and means responsive to barometric conditions of the atmosphere to regulate the speed of the pump.

24. Means for supplying an explosive mixture of hydrocarbon and air to explosion engines having shafts comprising a mixing device having means for supplying hydrocarbon and air thereto, the air supplying means embracing a pump, means for driving the pump, including a speed change mechanism, intermediate the pump and the engine shaft, and means responsive to barometric pressure for controlling the change speed mechanism.

25. The combination with an explosion engine having a shaft, of means for supplying a mixture of hydrocarbon and air thereto, the air supplying means embracing a pressure device, with means for driving it from the shaft, and means responsive to barometric pressures for controlling the speed of said pressure device.

26. The combination with an explosion engine, of means for supplying a mixture of hydrocarbon and air thereto, the air supplying means embracing a pressure device, a change speed mechanism connecting the engine to the pressure device for driving the latter, and means responsive to barometric pressures for controlling the speed change mechanism.

27. Means for supplying a mixture of hydrocarbon and air to explosion engines comprising a mixing device having means to direct a hydrocarbon and air to the mixing device, and means responsive to barometric pressure for controlling the pressure of air delivered to the mixing device, said latter means being constructed with means to disconnect the pressure controlling means at a predetermined barometric pressure.

28. Means for supplying a mixture of hydrocarbon and air to explosion engines com-

prising a mixing device, with means for directing hydrocarbon and supplying air thereto, said air supply means embracing a pump, means to drive said pump, including

5 speed change mechanism, and means responsive to barometric pressures for regulating the speed change mechanism, embracing means to disconnect the regulating means for the change speed mechanism at

10 a predetermined barometric pressure.

29. The combination with an internal combustion engine, of means for supplying a mixture of hydrocarbon and air thereto, embracing means responsive to altitudinal

15 variations of atmospheric conditions to regulate the pressure of air supply to the mixture, and constructed and arranged to automatically throw out the regulating means at a predetermined pressure.

20 30. The combination with an internal combustion engine, of means for supplying a mixture of hydrocarbon and air, comprising a mixing device with means for directing hydrocarbon and supplying air, said air supply means embracing a pump, means to drive said pump, including speed change mechanism, and means responsive to barometric pressures for regulating the speed change mechanism, and constructed and ar-

25 ranged to render the speed change mechanism inoperative to drive the pump at a predetermined barometric pressure.

31. The combination of an internal combustion engine of means for delivering gaseous mixture to the engine, a rotary blower for supplying air, and means for driving the blower from the engine having provision for maintaining the speed of the blower substantially constant irrespective of variations in engine speed.

32. The combination with an internal

combustion engine, of means for delivering gaseous mixture to the engine including a compressor and variable speed driving devices for driving the compressor from the engine, mechanism actuated by the power of the engine for adjusting said devices, and means operating automatically for controlling the adjusting mechanism.

33. The combination with an internal combustion engine, of means for delivering gaseous mixtures to the engine including a compressor and variable speed devices for driving the compressor from the engine, an engine driven pump for circulating liquid, means actuated by the pressure of the liquid for adjusting the driving devices, a valve for regulating the flow of the liquid to control its pressure, and means for actuating the valve.

34. The combination with an internal combustion engine having a shaft, of a carburetor having an air-intake, a compressor connected directly to the intake for producing supplementary pressure therein, variable speed driving devices between the compressor and the engine shaft, and automatically acting mechanism responsive to variations in the air-intake pressure for controlling said devices.

35. The combination with an internal combustion engine having a shaft, of means for delivering gaseous mixture to the engine, auxiliary devices including a compressor driven from the engine shaft at variable speed for producing supplementary pressure of the gaseous mixture, automatically acting mechanism responsive to variations in air pressure for controlling said devices, and means adapted to be actuated by the operator for controlling said devices.

HARRY E. MORTON.
